UNITED STATES PATENT OFFICE.

ADOLPH M. HOLSTEIN, OF SYRACUSE, NEW YORK.

DESIGN FOR FURNITURE, CASKET, INTERIOR OR EXTERIOR DECORATION.

52,166.

Specification for Design.

Patented July 9, 1918.

Application filed August 22, 1917. Serial No. 187,548. Term of patent 3½ years.

To all whom it may concern:

Be it known that I, ADOLPH M. HOLSTEIN, a citizen of the United States, residing at Syracuse, in the county of Onondaga and State of New York, have invented a new and original and ornamental Design for Furniture, Casket, Interior or Exterior Decoration, of which the following is a specification, reference being had to the accompanying drawing, forming a part hereof.

The drawing is a face view or front elevation of my design.

This design consists of a centrally located conventional shell oval in general form and having a lobed or serrated edge, moldings including horizontal portions extending laterally relatively to the shell and having downwardly and outwardly curved portions terminating in foliated ends, foliated work extending from under the shell laterally in opposite directions beneath the horizontal portions of the moldings and over the horizontal portions of the molding and upwardly around the shell to a point near the central portion thereof.

I claim:

The ornamental design for furniture, casket, interior or exterior decoration, substantially as shown and described.

In testimony whereof, I have hereunto signed my name, at Syracuse, in the county of Onondaga, and State of New York, this 29th day of June, 1917.

ADOLPH M. HOLSTEIN.
